UNITED STATES PATENT OFFICE

Patent No. 2,381,792

EXTERIORMLY ILLUMINATED REFLECTOR FOR LIGHTING FIXTURES

George P. Wakefield, Vermilion, Ohio, assignor
to The F. W. Wakefield Brass Company, Vermilion, Ohio, a corporation of Ohio

Application September 16, 1942, Serial No. 458,524

3 Claims. (Cl. 240—78)

The present invention, relating as indicated to lighting fixtures, has more particular regard to the improvement of such fixtures where designed primarily for use in indirect lighting. In such fixtures, as is well understood, a more or less opaque reflector of varying form is placed beneath the light source to direct the light therefrom upwardly either against the ceiling or other specially provided reflecting surface. While this arrangement has well recognized advantages, such reflector is present as a dark object in the area of illumination and is more or less obtrusive.

An object of the present invention accordingly is to provide means whereby from the same light source the exterior of such a reflector as is used in indirect lighting may be sufficiently illuminated to avoid the effect just noted.

Another object is to provide means for effecting the result stated which will at the same time provide an ornamental effect.

To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a perspective view of an indirect lighting fixture designed to be suspended from the ceiling of a room, such fixture embodying my present improvements;

Fig. 2 is a transverse section of such fixture;

Fig. 3 is a broken sectional view thereof taken on a plane indicated by the line 3—3 Fig. 2;

Fig. 4 is a transverse section, similar to that of Fig. 2, but more or less diagrammatic in character, and illustrating a modification in construction; and

Fig. 5 is a perspective view similar to that of Fig. 1 but illustrating a different type of indirect lighting fixture.

The fixture illustrated in Fig. 1 is not only of the type designed for indirect lighting, but is of elongated form so as to be adapted to receive one or more elongated illuminators such as, for example, the fluorescent lighting tubes which are becoming increasingly popular as a source of illumination for working spaces as well as for offices and rooms in residences.

As best illustrated in Fig. 2, such illustrative fixture is designed to be suspended from a ceiling

50 in a room, and is provided with a main frame or housing 2 which is provided with a removable cover 3 and is adapted to receive, in addition to the necessary wiring, such special equipment as a ballast box 4 required where fluorescent lighting tubes are employed. The illustrated fixture includes two sockets or receptacles 5 at each end adapted to receive and provide electric connection for the corresponding ends of two such tubes 6.

The opaque reflector employed with the fixture may take on various forms, the one shown comprising end members 10 and angularly related side parts 11 and bottom parts 12, such side and bottom parts being exteriorly concave in a transverse direction. The latter may be two in number, as shown in Fig. 2, or as shown in Fig. 4 and as will be presently described in more detail, more than two such transversely concave bottom parts may be utilized in the reflector. The interior surfaces of such component parts of the reflector will be bright plated or otherwise finished to direct upwardly and outwardly from a plane defined by the upper edges of the reflector the

10 light from the tubes 6 or other equivalent sources contained within the fixture.

15 Along the meeting edges of the side and bottom parts of the reflector, slits 13 are provided and secured in alignment with each such slit, without the reflector is a combined light reflecting and diffusing element 16. Any suitable means may be employed thus to secure said element in place as, for example, transverse webs or clips 14 which span the slits and screws 15 which pass therethrough and engage the element at intervals. The element will preferably be comprised of translucent, slightly diffuse, plastic tubing.

20 As a result of the construction and arrangement of parts just described, that part of the light radiating downwardly from each of tubular illuminators 6 which strikes the corresponding slit 13 will pass therethrough and in turn strike the element 16 aligned with such slit, the rays of light in question being indicated by the small arrows within the tubular body of the element

25 at the lower right hand corner of Fig. 2. Because of the translucent character of the tubular element, such rays of light will in part serve to illuminate the latter and in part will be reflected from the interior surface generally in the directions indicated by the longer arrows on the same figure. Such reflected rays will strike against the exteriorly concave surfaces of the side and bottom parts of the reflector so as to illuminate

30 the latter, the degree of such illumination being

35 40 45 50 55

capable of being varied as desired by varying the width of the slits 13, the degree of translucency of the tubular elements 16, and the diameter of the latter, as will be readily understood. While the character of the finish of such exterior surfaces of the reflector parts in question will determine the degree to which they constitute a secondary light source, the primary object sought is merely to lighten the dark side of the reflector.

In the modification illustrated in Fig. 4, as previously indicated, the principal difference lies in the provision of an increased number of bottom parts 12 in the reflector. Thus four instead of two are shown, these, as before, being outwardly concave in a transverse direction, just as are the side parts 11 of the reflector. The fixture, as further shown, is designed to be fitted with four elongated tubular illuminators 6, one being located more or less directly above each of such bottom reflector parts 12. In addition to having the combined light reflecting and diffusing elements disposed along slits at the meeting lines of the side parts 11 and adjacent bottom parts 12, similar such elements are provided at the meeting edges of the bottom parts themselves, so that each of the latter will be externally illuminated in the same manner as described above in connection with the first form of the fixture. Furthermore, along lines intermediate of and preferably centrally located with respect to the edges of the several bottom parts 12 of the reflector, I attach narrow ribs of plastic material, which may be slightly frosted, which will stand out when the rays of light which are reflected from the tubular elements 16 strike thereagainst. An additional ornamental effect, as well as an additional diffusion of light from the exterior of the otherwise opaque reflector is thus obtained.

The principle of my improvement is of course not limited in application to an elongated type of fixture, as illustrated in Fig. 1, but as shown in Fig. 5 it may equally well be applied to a fixture of general cylindrical or frustro-conical form. Here the annular side part 20 of the reflector is outwardly concave as before and the bottom part 21 is likewise outwardly concave from its periphery to a central point. The combined light reflecting and diffusing element 22 will be of circular form, fitted to a corresponding slit that is provided along the meeting circular line of such side and bottom parts of the reflector.

It will be understood that in referring to the reflector in my improved fixture as opaque, this

term is intended to connote any of the usual types of reflecting material which are employed in fixtures of the so-called indirect lighting type. It will be further understood that while I have illustrated my improved construction as applied to pendent fixtures, such construction may be equally advantageously employed in connection with side wall fixtures of the type in question.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a lighting fixture of the indirect type, the combination of an opaque reflector comprising parts presenting oppositely concaved angularly related exterior surfaces, a narrow slit being provided along the meeting edges of such surfaces, and a tubular, cylindrical element of translucent material disposed without said reflector in close fitting alignment parallel with such slit, said element being of substantially greater diameter than such slit and the interior surface of said element being formed and disposed to reflect light passing through said slit onto such exterior surfaces of said reflector parts.
2. In a lighting fixture of the indirect type adapted to receive one or more elongated illuminators, the combination of an opaque reflector comprising elongated, exteriorly concave side parts in approximate parallelism with said illuminators, and an exteriorly concave bottom part, slits being provided along the meeting edges of said side and bottom parts, and a tubular, cylindrical element of translucent material disposed without said reflector in alignment with each such slit.
3. In a lighting fixture of the indirect type adapted to receive one or more elongated illuminators, the combination of an opaque reflector comprising elongated, exteriorly concave side parts in approximate parallelism with said illuminators, and an exteriorly concave bottom part, slits being provided along the meeting edges of said side and bottom parts, a tubular, cylindrical element of translucent material disposed without said reflector in alignment with each such slit, and an element of similar material attached to said bottom reflector part intermediately of said first-named elements.

GEORGE P. WAKEFIELD.
